UNITED STATES PATENT OFFICE

HENRY CHIPMAN MILLER AND EDGAR HARRY DAINTON, OF LONDON, ENGLAND

HYDRAULIC JACK

Application filed August 23, 1928, Serial No. 301,564, and in Great Britain August 30, 1927.

This invention relates to hydraulic and other fluid pressure jacks of the kind in which the lower end of the ram cylinder is screwed or otherwise secured to the base casting and is housed in the reservoir for the oil or other motive fluid utilized for operating the jack.

The object of the present invention is to simplify and improve the construction of jacks of the kind referred to so as to enable the base and reservoir to be economically produced and to be rapidly and accurately assembled and secured, thus effecting considerable economies in manufacture.

According to the present invention in a jack of the kind referred to the motive fluid reservoir is formed by assembling to the base casting a loose shell or casing which is arranged concentrically of the fixed ram cylinder and is clamped fluid tight to the base casting by means of a perforated cover member that is adjustably coupled to the upper end of the fixed ram cylinder.

In a convenient construction the base casting is formed with concentric recesses, the inner recess being tapped to receive the externally threaded lower end of the ram cylinder which is screwed therein, while the external concentric recess is furnished with packing and adapted to receive the lower end of the reservoir shell or casing.

The upper end of the ram cylinder is also externally screw-threaded so as to engage with a counterpart screwthreaded perforated end-plate or with a threaded nut or sleeve that carries the end-plate, which end-plate is adapted to form the cover of the reservoir and is grooved or recessed to receive the upper end of the shell or casing so that the latter is firmly clamped to the base by screwing down the end-plate on the ram cylinder or on the threaded sleeve or nut secured on the latter.

In the case of a jack having a simple ram, i. e. one with a single lift, the perforated end-plate forming the cover may be provided with an internally threaded socket which is adapted to screw on to the upper end of the ram cylinder and also to form the stuffing box through which the ram works, while in

the case of a jack provided with a telescopic ram having two or more lifts the internally threaded socket of the perforated end-plate is adapted to screw on to an externally threaded nut or sleeve which forms the ram stop and gland of the stuffing box through which the lower lift of the telescopic ram works.

Embodiments of the present invention are illustrated by way of example in the accompanying drawings wherein similar references indicate like parts.

Figure 1 is a vertical section illustrating a hydraulic jack having a simple or single lift ram constructed in accordance with the present invention; while

Figure 2 is a similar view of a hydraulic jack having a two-lift telescopic ram.

In the drawings:—

1 indicates the base casting of the jack, 2 the ram cylinder, 3 the ram, 4 the shell or casing of the reservoir and 5 the adjustable perforated end-plate forming the cover of the reservoir.

A suitable force pump 20 and release valve 21 together with distributing and circulating passages indicated at 22 are mounted and arranged in the base casting 1 for circulating motive fluid between the reservoir and the ram cylinder 2 to operate the ram 3 in known manner.

In the constructions illustrated, the ram cylinder 2 is externally screw-threaded at its upper end 2^a and lower end 2^b, while concentric recesses 6 and 7 are formed in the base casting 1 to receive respectively the lower ends of the ram cylinder 2 and cylindrical shell or casing 4, which shell or casing is assembled to the base casting 1 concentrically with the ram cylinder to form the motive fluid reservoir.

The inner recess 6 of the base casting is internally screw-threaded to engage the counterpart screw-threaded lower end 2^b of the ram cylinder, the bottom surface of such recess being machined to form an accurate seating for the machined lower edge of the ram cylinder 2 when the latter is screwed into such recess.

The reservoir shell or casing 4 is secured to the base casting 1 by means of the perforated

end-plate 5 which screws over the upper end of the ram cylinder 2 so as to form the cover of the reservoir. The lower end of the shell or casing is adapted to make a sliding fit with the outer concentric recess 7 in the base casting 1, while its upper end makes a similar fit with a counterpart groove or recess 8 formed in the adjacent surface of the end-plate 5.

As illustrated at Figure 1, the perforated end-plate 5 is formed with an internally threaded central socket 10 which is adapted to screw on to the externally threaded upper end 2^a of the ram cylinder 2 so as to form the stuffing box through which the ram 3 works in the ordinary way.

The socket 10 is shouldered down as indicated at 11 to form the perforation through which the ram passes, and also a recess to receive an annular packing 13 together with a gland and stop ring 14, which latter seats against the adjacent upper edge of the ram cylinder 2.

The reservoir shell or casing 4 is firmly clamped to the base casting 1 by screwing down the end-plate 5 upon the threaded upper end of the ram cylinder 2, which operation simultaneously compresses the ram packing 13 and leather or other packing 15 arranged in the recesses 7 and 8 for the upper and lower edges of the reservoir shell or casing 4.

In the modification illustrated at Figure 2 the perforated end-plate 5 is screwed on to an externally screw-threaded sleeve 16 which screws on to the externally threaded upper end 2^a of the ram cylinder 2, and forms the gland and stop ring for the lower lift or section of the telescopic ram 3.

In this construction the internally threaded socket 10 screws on to the externally screw-threaded sleeve 16 and is shouldered down at 11 to form the perforation through which the lower lift or section of the telescopic ram 3 works, and also the recess for the annular packing 13 for such ram section.

The sleeve or nut 16 is also shouldered down as indicated at 17 to form the gland and stop ring for the lower lift or section of the ram.

The reservoir shell or casing 4 is clamped to the base casting 1 by screwing down the end-plate 5 on the sleeve 16, which operation compresses the ram packing 13 and also the leather or other packing 15 at the upper and lower ends of the reservoir shell or casing, as described with reference to Figure 1.

We claim:—

1. A hydraulic or other fluid pressure jack having a fixed ram cylinder furnished with an adjustable externally screw-threaded sleeve adapted to form a stop collar for the ram working in said cylinder, and a reservoir for the motive fluid formed by means of a loose shell or casing assembled to the base concentrically of said cylinder and clamped in position by a cover plate formed

with a central perforated socket and a concentric recess, said socket being adapted to make threaded engagement with said externally threaded sleeve and to form in combination therewith a gland and stuffing box for the ram.

2. A hydraulic or other fluid pressure jack, having a reservoir for the motive fluid formed by means of a loose shell or casing assembled to the base concentrically of a fixed ram cylinder and clamped fluid tight in position by a perforated cover plate formed with a central perforated socket and a concentric recess and comprising an outer annular member threaded internally and an inner externally and internally threaded stop ring in engagement with the externally threaded upper end of said ram cylinder, said socket being adapted to house an annular packing and to form, in combination therewith, a gland and stuffing box for the ram.

In testimony whereof we affix our signatures.

HENRY CHIPMAN MILLER.
EDGAR HARRY DAITON.
